UNITED STATES PATENT OFFICE.

AARON J. TYLER, OF ROCHESTER, NEW YORK; JOHN B. ABBOTT EXECUTOR OF THE ESTATE OF SAID AARON J. TYLER, DECEASED.

THERAPEUTIC ELECTRODE.

Application filed September 10, 1921. Serial No. 499,595.

To all whom it may concern:

Be it known that I, AARON J. TYLER, a citizen of the United States, residing at Rochester, in the county of Monroe and State of New York, have invented certain new and useful Improvements in Therapeutic Electrodes, of which the following is a specification.

This invention relates to appliances for the therapeutic application of the electric current, and more particularly to an electrode in the form of a metallic mat adapted to be applied to the part of the body to be treated.

One of the primary objects of the present invention is to provide a mat which, notwithstanding its necessarily metallic nature, will be so constructed as to conform closely to the contour of the part of the body to be treated and against which it is applied. Considerable inconvenience and sometimes injury results from the use of electrodes of the usual type inasmuch as if any part of the electrode is placed close to the body

without being in actual contact therewith, a spark gap will be produced, and the treatment becomes painful both during the period of application of the electrode and also subsequently, if the flesh is blistered.

Therefore the present invention contemplates the provision of an electrode in the form of a flexible metallic mat adapted to be laid in close contact with the part of the body to be treated and to conform closely to the contour of such part so that there will be no likelihood of some one portion or another of the mat becoming displaced so as to be spaced from the body and form a spark gap.

Another object of the invention is to provide, in connection with a mat of the type above outlined, novel means whereby a conductor terminal may be readily electrically connected with the mat and without any likelihood of the weight of the conductor or a pull thereon causing displacement of the mat.

In the accompanying drawings:

Figure 1 is a perspective view illustrating the mat embodying the invention in use;

Figure 2 is a plan view in detail of the mat;

Figure 3 is a perspective view illustrating the connection provided for the conductor terminal.

The mat embodying the invention is indicated in general by the numeral 1 and the same may be made in various sizes and of various marginal contours depending upon the use to which the mat is to be put. Thus, the mat may be made in sizes to adapt them for application to various parts of the body and of relatively large area, and they may equally as well be made in much smaller sizes for application to other parts of the anatomy. The mat 1 in any event comprises a sheet of metallic mesh consisting of small interlocked rings or links, and it will be understood, as the dimensions of the mat may in general be varied, so likewise may the size of the mesh be varied to suit conditions. Likewise any metal found suitable for the purpose may be employed so long as it is a good conductor of electricity, and it will no doubt be preferable to make use of a metal which is non-corrod़ing.

The mat 1 is marginally bound as indicated by the numeral 3, by tape, a cloth hem, or in any other manner found desirable, and also material may be employed for this purpose other than cloth. In the illustrated embodiment of the invention there is shown a mat which is of dimensions and marginal contour adapting it for general application to the major parts of the body as for example to the back or to the limbs, and in order that the mat may be securely held in place after it has been arranged in contact with the portion of the body to be treated, attaching tapes may be secured to the margin of the mat at suitable points. In the present instance, tapes 4 will be secured to the upper corners of the mat, tape 5 to the lower corners, and other tapes 6 to the opposite sides of the mat at any point suitably spaced between the attached ends of the tapes 4 and 5. In this arrangement, the tapes 5 and 6 may be passed and tied about the body at and above the waist line, assuming that the mat is to be applied to the back in about the position illustrated in Figure 1 of the drawings, and the other tapes 4 may be led upwardly and over the shoulders and tied at their free ends so as to support the mat against downward displacement.

At this point it will be evident that the mat, being of mesh material will, when applied to any part of the anatomy, closely

conform to the contour thereof, automatically, and without the necessity of a careful arrangement of the various portions of its area. Consequently in making use of the mat embodying the invention the patient being subjected to treatment, is not liable to suffer any inconvenience or injury such as is occasioned in the use of the ordinary electrode having an inflexible contact surface.

10 Also it will be evident that, because of the peculiar character of the contact surface of the mat embodying the invention, the surface will conform closely to the contour of any part of the body upon which the mat is laid, the mesh accommodating itself automatically to depressed portions of the body surface as well as to raised portions thereof.

The mat will of course be employed in connection with an electrical conductor usually in the nature of a flexible conductor cord which is indicated in the drawings by the numeral 7, and such cords are ordinarily provided at their extremities with terminals 8 such as the one illustrated in the drawings and comprising a clasp adapted for application to and connection with the parts to which electric current is to be supplied.

to which electric current is to be supplied. As heretofore stated there is provided, in connection with the mat 1, a device whereby the clip 8 of the conductor cord 7 may be electrically connected with the mat without likelihood of the weight of the cord or any pull exerted thereon causing displacement of the mat to space any portion of the area thereof from the surface of the body. The means referred to comprises two members indicated one by the numeral 9 and the other by the numeral 10. The member 9 constitutes a bearing member and is preferably in the nature of a flat strip of sheet metal which is disposed against the inner surface of the mat and is designed to rest snugly against the surface of the body when the mat is laid over the part to be treated. The member 10 constitutes a connecting member and is preferably formed from sheet metal and comprises a flat sided body 11 provided with a shank portion 12 offset with relation to the body 11 preferably in a plane substantially parallel thereto, by an intervening bend 13. A rivet or pivot pin or similar connecting or fastening element 14 is secured through the shank portion 12 of the member 10 and through one end of the member 9, passing also through the mat 1, and this element 14 serves to pivotally connect the members 9 and 10 to the mat so that these members may be swung in unison in any desired direction about the

element 14 as a center. By reason of the 60
bend 13 in the shank 12 of the member 10,
the body 11 of the said member is spaced
with relation to the mat 1 a sufficient dis-
tance to permit of the ready application
of the clip 8 to the body 11 of the said 65
member 10. The clip may be applied at
the most convenient angle and it will be
understood that after the mat has been ap-
plied and bound to the body, and the clip
8 of the conductor cord 7 is attached to the 70
body 11 of the member 10, the cord will as-
sume a position of repose, and because of
the pivotal connection of the member 10
with the mat, this member will swing about
its pivot to accommodate itself to the posi- 75
tion assumed by the cord. In like manner
should the cord be displaced in any direc-
tion, the member 10 will pivot upon the mat
to assume a position permitting of the
changed position of the cord and this with- 80
out in any way lifting the mat from the
body so as to space the same and cause the
formation of a spark gap.

Having thus described the invention, what is claimed as new is: 85

1. A therapeutic electrode comprising a flexible contact member, a bearing member disposed against one surface of the contact member and adapted to rest upon the surface of the body when the electrode is in use, a connecting member comprising an attaching shank portion disposed against the other surface of the contact member opposite one end of the bearing member, a pivot pin fitted through the connecting member and contact member and providing for free independent adjustment of the said contact and connecting members, the connecting member having a portion offset with relation to its shank and of substantially flat circular form adapting it for the connection thereto, at various angles and in various positions, of a conductor terminal clip. 90 95 100

2. A therapeutic electrode comprising a flexible contact member, a pivot pin supported upon the said member, and a connecting member comprising an attaching shank portion pivotally connected with the said pivot pin and resting flat upon the surface of the flexible contact member, the said shank portion having an upwardly inclined portion, and a portion of substantially flat circular form supported at the upper end thereof and thereby spaced from the surface of the said flexible contact member. 105 110 115

In testimony whereof I affix my signature.

AARON J. TYLER. [L. S.]
